JACQUARD FABRIC

Julius A. Hirsch, Chicago, Ill.

Application May 31, 1950, Serial No. 10,268

Term of patent 14 years

(Cl. D92—1)

To all whom it may concern:

Be it known that I, Julius A. Hirsch, a citizen of the United States, residing at Chicago, county of Cook, and State of Illinois, have invented a new, original, and ornamental Design for Jacquard Fabric, of which the following is a specification, reference being had to the accompanying drawing, forming a part thereof, in which the single figure is a plan view of the jacquard fabric, showing my new design.

I claim:

The ornamental design for a jacquard fabric, as shown and described.
